ELECTRICAL CONTACT MEANS

Harry A. Douglas, Bronson, Mich., assignor to
 Kingston Products Corporation, a corporation
 of Indiana

Continuation of application Serial No. 8,315, Feb-
 ruary 26, 1935. This application April 30, 1938,
 Serial No. 205,299

10 Claims. (Cl. 200—166)

My invention relates to electrical contact means, such as may be used in electric switches and the like, and more particularly to electrical contacts and terminals associated therewith, and the principal object of my invention is to provide a new and improved electrical contact means of this type. In the drawing accompanying this specification, and forming part of this application, I have shown, for purposes of illustration, one form which my invention may assume.

This application is substituted for my formally abandoned application, filed February 26, 1935, Serial Number 8,315.

15 In the drawing:

Figure 1 is a vertical sectional view of one form of my invention, as it may be embodied in an electrical switch, with certain duplicate parts omitted.

20 Figure 2 is a fragmentary rear elevation of the base of the switch shown in Figure 1, with part of the electrical contacts assembled with the base,

25 Figure 3 is a section taken on the line 3—3 of Figure 1, looking in the direction of the arrows, and

Figure 4 is a perspective view of parts, disassembled, included in a contact means, shown in Figure 1.

30 Referring to Figure 1 of the drawing, a panel 10 has mounted thereon a switch casing 11, of cup-shape, having a bottom 12 and a tubular portion 13 extending therefrom. Fastened to the bottom 12 in any suitable manner is a threaded nipple 14 extending through an aperture in the panel 10, and engaged by a nut 15. A shaft 16 is disposed through the nipple 14 and is provided at one end with an operating handle 17. At the other end the shaft 16 is provided with a 35 laterally extending member 18 drivingly connected in any suitable manner to an insulating carrier 19.

The insulating carrier 19 is here shown as provided with an electrical contact 20 having a 40 plurality of depressions, two of which, 21, 22, are visible. The insulating carrier 19 is also provided with a plurality of depressions, one of which, 23, is visible.

45 Cooperable with the insulating carrier 19 and the contact 20 mounted thereon are a plurality of contact means, in this particular switch seven in number, three of which, 24, 26, 27, are visible in Figure 1, whereas two more, which would be otherwise visible in Figure 1, have been omitted 50 for the sake of clearness. Inasmuch as all of

the contact means, such as 24, 26, 27, are identical, only one of them will be described in detail.

The contact means 24 is here shown as of generally U-shape and desirably formed to that shape from flat stock, desirably of iron or steel. The U-shaped contact means 24 has legs 28, 29, reciprocably mounted in an insulating base 30. The base 30 is of suitable configuration to be received by the open end of the casing 11 and 5 may be fastened to the casing in any suitable manner (not shown). The inner face of the insulating base 30 is provided with a recess 31, extending at right angles to a radius of the base, and having a circumferential width and a 10 radial width sufficient to slidably receive the leg 28 of the contact means 24. The recess 31 extends axially of the insulating base 30 to and merges with an aperture 32 in a boss 33 provided on the outer face of the insulating base 15 20 30. The aperture 32 has a cross-sectional shape similar to the cross-sectional shape of the leg 28. The bosses provided for the other contact means 24, 25, 26, 27 are identical with the boss 33 associated with the contact means 24, so 25 that reference may be had to Figure 2 where one of the contact means has been removed from a boss 33 to more clearly show the apertures therein. The insulating base 30 is also provided on its inner face with a recess 34 extending at 30 right angles to a radius of the base, the circumferential width of the recess 34 being sufficient to slidably receive the leg 29 of the contact means 24. The recess 34 is less in circumferential width than the recess 31, the leg 29 being 35 of less width than the leg 28. The recess 34 extends axially of the base 30 to, and merges with, an aperture 35 in the boss 33, which aperture may also be seen in Figure 2. The aperture 35 has a cross-sectional shape similar to that 40 of the leg 29. The recesses 31, 34 are joined by a recess 36 having arcuate walls 37, 38 which at one end merge with the circumferential ends of the recess 34 and at the other merge with the radially inner side of the recess 31, at points 45 spaced circumferentially from the circumferential ends of the recess 31. The recess 36 extends axially to a point where the recesses 31, 34 merge with the apertures 32, 35 in the boss 33.

The bight of the U-shaped contact means 24 50 is provided with a contact 39, desirably of brass, which contact in this instance is provided by an originally separate piece analogous to a rivet, the head of which serves as the contact and the shank of which passes through an aperture 55

in the bight of the U-shaped contact means 24 and is riveted or upset to fasten the contact; at the same time providing a projection 40. The projection 40 aids in holding in position one end 5 of a helical spring 41, disposed between the legs 28, 29, the other end of the spring 41 bearing against the bottom of the recess 36.

The leg 28 of the contact means 24 is longer than the leg 29, and extends through the insulating base 30 from the inner to the outer side thereof. At its outer end the leg 28 is provided with means for connecting an electrical conductor thereto comprising a screw 42 operable in a threaded hole through the leg 28. Underneath the head of the screw 42 is provided a lock washer 44 having a central aperture, toward which project, from the annular portion of the washer, a plurality of spaced teeth, each twisted out of its own plane so as to form serrations 45 projecting laterally from both faces of the washer. The serrations 45 are adapted to lock the screw 42 and also hold a conductor 48, which may be placed between the washer 44 and the leg 28. In order to prevent turning of 15 the washer 44 as the screws 42 turn, the washer is provided with a projection 46 extending transversely to a face of the washer and adapted to be received in an aperture 47 provided in the leg 28.

30 In assembling a contact means such as 24 with the base, let it be assumed that the screw 42 and washer 44 are not yet assembled with the leg 28. The spring 41 is positioned to have one end thereof disposed about the projection 40, and the legs 28, 29 are then inserted in the recesses 31, 34, the leg 28 passing through the aperture 32 in the boss 33. The washer 44 is then placed in the position shown in Figure 1 with the projection 46 through the aperture 47, and the screw 40 42 is placed through the aperture in the washer and threaded into the leg 28. It will be clear that the projection 46 prevents such movement of the contact means 24, toward the right, as viewed in Figure 1, as would permit the spring 45 41, or the contact means as a whole, from becoming disassembled from the base 30. The same procedure is followed with all of the rest of the contact means, similar to the contact means 24, it may be desired to have mounted on 50 the base 30. The base 30, with the contact means assembled therewith, may then be assembled with and fastened to the switch casing 11 having the contact carrying member 19 disposed therein. The springs 41 then bias the contacts into engagement with a contact, such as 20, carried by the insulating contact carrier 19 or into engagement with the insulating contact carrier itself, depending upon the relation of the parts.

60 It will be evident that in the particular construction illustrated in Figure 1, since the contacts 39 of the contact means 24, 26 are in engagement with the contact 20, an electrical connection will be formed between the contact means 24, 26, and, on the other hand, the contact 39 of the contact means 27, since it is in engagement with the insulating carrier 19 is not included in any completed circuit. However, the form and disposition of the contacts, such as 20, on the relatively movable element of the switch, 65 and the number and arrangement of the contact means, such as 24, 25, 26, 27, is not material, as far as the present invention is concerned, and it will be obvious to those skilled in the art that any desired arrangement and relation may 70 be adopted, which will permit of performance

of the desired switching operations when the handle 17 is turned.

In view of the foregoing it will be obvious to those skilled in the art that my invention may be embodied in other constructions wherein the 5 relatively movable elements may cooperate in ways other than that disclosed and may assume a variety of forms, variously changed and modified within the spirit of the invention.

In general it will be clear to those skilled in 10 the art that the features of my invention need not all be used in one embodiment, and may be individually or collectively variously changed and modified, without departing from the spirit of 15 the invention, or sacrificing all of the advantages thereof, and accordingly that the disclosure herein is illustrative only, and that my invention is not limited thereto.

What I claim and desire to secure by Letters 20 Patent is:

1. Terminal means, comprising: a support, 25 having an aperture; a body, slidably mounted in said aperture, and having portions extending from opposite surfaces of said support, one of said portions having means providing for the connection of a conductor, and having also an aperture; resilient means, engaging the other portion of said body, and constructed and arranged to urge said body in one direction with respect to said support; and means for preventing 30 unintentional disconnection of the conductor from said connection means, said preventing means having a part disposed through the aperture in said one portion, and constructed and arranged for engagement with a surface of said support to limit movement of said body in said 35 one direction.

2. Terminal means, comprising: a support, 40 having an aperture; a body, slidably mounted in said aperture, and having portions extending from opposite surfaces of said support; resilient means, engaging one portion of said body, and constructed and arranged to urge one portion 45 in a direction away from said support; the other portion of said body having an aperture, and having also means for connecting a conductor to said body, said connecting means including washer means having a part disposed through the aperture in said other portion, and constructed and arranged to engage the adjacent 50 surface of said support to limit movement of said body in said direction.

3. Terminal means, comprising: a support, 55 having spaced apertures, and having a well communicating with said apertures; a body, having spaced legs arranged for sliding movement through respective apertures, at least one of said legs having portions extending from opposite surfaces of said support; resilient means, constructed and arranged to urge said body in one direction away from said support; one portion of said one leg having an aperture, and having also means for connecting a conductor to said body, said connecting means including washer 60 means having a part disposed through the aperture in said one portion, and constructed and arranged to engage the adjacent surface of said support to limit movement of said body in said one direction.

4. Terminal means, comprising: a support, 65 having spaced apertures of unequal width, and having also a well communicating with said apertures; a U-shaped body, having its legs arranged for sliding movement through respective aper- 70

tures, each of said legs being of a width corresponding to the width of a respective aperture; the bight of said body being disposed adjacent one surface of said support, and one of said legs 5 extending through its respective aperture and having a portion disposed adjacent the opposite surface of said support, said portion being provided with an aperture; resilient means interposed between said bight and the bottom of said 10 well for urging said body in one direction; and means for connecting a conductor to said portion of said one leg, said means including washer means having a part disposed through the aperture in said portion and constructed and arranged 15 to engage said opposite surface of said support to limit movement of said body in said one direction.

5. Terminal means, comprising: a support, having an aperture; a body, slidably mounted in 20 said aperture, and having portions extending from opposite surfaces of said support, one of said portions having means providing for the connection of a conductor, and having also an aperture; the other portion of said body, being constructed and arranged to project with respect to 25 said support to engage contact means; and means for preventing unintentional disconnection of the conductor from said connection means, said preventing means having a part disposed through 30 the aperture in said one portion, and constructed and arranged for engagement with a surface of said support to limit movement of said body in said one direction.

6. Terminal means, comprising: a support, 35 having an aperture including a slot; a body, slidably mounted in said aperture, and having portions extending from opposite surfaces of said support, one of said portions being slidable in said slot and having means including a screw 40 providing for the connection of a conductor, and having also an aperture; resilient means, engaging the other portion of said body, and constructed and arranged to urge said body in one direction with respect to said support; and means 45 for preventing unintentional disconnection of the conductor from said connection means, said preventing means having a part disposed in the aperture in said one portion, and constructed and arranged for engagement with a surface of said 50 support to limit movement of said body in said one direction.

7. Terminal means, comprising: a support, having an aperture; a body, slidably mounted in said aperture, and having portions extending

from opposite surfaces of said support; one portion of said body constructed and arranged to engage contact means; the other portion of said body having an aperture, and having also means for connecting a conductor to said body, said connecting means including washer means having a part disposed through the aperture in said other portion, and constructed and arranged to engage the adjacent surface of said support to limit movement of said body in said direction. 10

8. Terminal means, comprising: a support, having spaced apertures; a body, having spaced legs arranged for sliding movement through respective apertures, at least one of said legs having portions extending from opposite surfaces 15 of said support; resilient means, constructed and arranged to urge said body in one direction away from said support; one portion of said one leg having an aperture, and having also means for connecting a conductor to said body, said connecting means including washer means having a part disposed in the aperture in said one portion, and constructed and arranged to engage the adjacent surface of said support to limit movement 20 of said body in said direction. 25

9. Terminal means, comprising: a support, having a well, and spaced apart apertures arranged tangentially to said well and communicating therewith; a body, having spaced legs arranged for sliding movement through respective apertures, at least one of said legs having portions extending from opposite surfaces of said support; resilient means, constructed and arranged to urge said body in one direction away 30 from said support; one portion of said one leg having an aperture, and having also means for connecting a conductor to said body, said connecting means including washer means having a part disposed through the aperture in said one portion, and constructed and arranged to engage the adjacent surface of said support to limit movement 35 of said body in said direction. 40

10. Terminal means, comprising: a body having a pair of parallel portions joined together at one end by a bight portion extending at right angles 45 to said parallel portions, one of said parallel portions and said bight portion being of the same width, a contact being provided on said bight portion, the other parallel portion being of a greater width and length than said one portion, 50 and provided with means to which a conductor may be secured.

HARRY A. DOUGLAS.
